Primary Examiner — Wan Laymon
Assistant Examiner — Mark Booker(57) **CLAIM**

The ornamental design for a wearable towel, as shown and described.

DESCRIPTION

FIG. 1 is a perspective view of the wearable towel of the present invention, shown being worn;

FIG. 2 is a top plan view of the wearable towel of the present invention and showing it lying flat;

FIG. 3 is a front elevation view of a wearable towel;

FIG. 4 is a rear elevation view of a wearable towel;

FIG. 5 is an enlarged partial view, showing the arm opening; and,

FIG. 6 is an enlarged partial view, showing the belt cord passing the transverse belt loop through the cutout opening.

1 Claim, 4 Drawing Sheets(56)
